Frankel, LLP.

(57) **CLAIM**

The ornamental design for a combination compressor/generator, as shown and described.

DESCRIPTION

FIG. 1 is a perspective view showing of a combination compressor/generator showing my new design;

FIG. 2 is a side elevation view thereof;

FIG. 3 is a side elevation view thereof, showing the opposite side of FIG. 2;

FIG. 4 is a top plan view thereof;

FIG. 5 is a bottom plan view thereof;

FIG. 6 is a rear elevation view thereof; and,

FIG. 7 is a front elevation view thereof.

It being understood that the broken lines are for illustrative purposes only.
